CLAIM

The ornamental design for a jewelry ring as shown and described.

DESCRIPTION

FIG. 1 is a perspective view of a jewelry ring showing my new design, in a partially unfolded configuration to show the articulating hinges that join the sections of the design; FIG. 2 is a front elevational view of the design, in a completely folded configuration;

FIG. 3 is a left side elevational view of the design, in a completely folded configuration, the right side elevational view a mirror image of this view;

FIG. 4 is a top plan view of the design, in a completely folded configuration;

FIG. 5 is a perspective view of the top right of the design, in a triangular folded configuration, the perspective view of the top left of the design a mirror image of this view;

FIG. 6 is a right elevational view of the design, in a triangular folded configuration, the left elevational view of the design a mirror image of this view;

FIG. 7 is a top plan view of the design, in a triangular folded configuration;

FIG. 8 is a bottom plan view of the design, in a triangular folded configuration; and,

FIG. 9 is a front elevational view of the design, in a triangular folded configuration, the rear elevational view of the design a mirror image of this view.

Any shading and cross-hatching are not features of the design but are utilized to illustrate the surface contours of the jewelry ring design in the drawings.
